UNITED STATES PATENT OFFICE.

JOHN T. NEEDHAM, OF BAYONNE, NEW JERSEY, ASSIGNOR OF ONE-HALF TO POSTAL TELEGRAPH-CABLE COMPANY, OF NEW YORK, N. Y., A CORPORATION OF NEW YORK.

ANNUNCIATOR.

No. 882,118.

Specification of Letters Patent. Patented March 17, 1908.

Application filed May 27, 1907. Serial No. 375,767.

To all whom it may concern:

Be it known that I, JOHN T. NEEDHAM, a subject of the King of Great Britain, and a resident of the city of Bayonne, county of 5 Hudson, State of New Jersey, have made certain new and useful Improvements in Annunciators, of which the following is a specification.

This invention relates to electro-magnetic 10 apparatus for indicating a change in the normal condition of an electric circuit.

The object of this invention is to provide an annunciator or indicating device that shall be effective from both sides of a telephone switchboard or operating table and to 15 combine with such indicator, spring jack switch connections so arranged that the insertion of a plug from either side of the board or partition shall restore the indicator to its 20 normal condition and to provide for operating a second or auxiliary signal, audible or visual, by the changed indication of the annunciator. Great benefit would result 25 from the use of this type of annunciator in telephone exchanges as the telephone circuit would be available at both the rear and the front of the switchboard thus reducing the size of the sections and also allowing two 30 operators to work on one section simultaneously without interfering with each other.

The accompanying drawings illustrate one arrangement of the invention applied to an operating table.

Figure 1 is a side elevation partly in section; Fig. 2 is a section through the line A, B, Fig. 1, showing the plug sockets and contact points of the spring jack; Fig. 3 is an elevation partly in section at right angles to Fig. 1; Fig. 4 is a horizontal section through the line 40 C, D, Fig. 1; Fig. 5 is an elevation of the annunciator showing the plug socket; Fig. 6 is a side elevation of the annunciator showing a plug in position; Fig. 7 is a plan view of a row of annunciators on the partition separating 45 opposite sides of a quartet table and Fig. 8 is a side elevation of part of the same.

There is a frame *f* of insulating material such as strips of vegetable fiber or a casting of insulating compound such as electrose. 50 An electro-magnet *m* having pole pieces *p* is fixed in the frame *f*; these pole pieces are angular and the armature *a* is fixed on a vertical spindle *s* journaled in the brass block *b* fixed in the frame *f*. A circular block *i* has

fixed to it or integral with it a target or 55 semaphore *t* which may bear a card with the number of the circuit; at right angles to this target on the lower side of the block *i* is a broad, flat projection *n* of insulating material fixed to the block *i*, this is perforated 60 at its center to receive the spindle *s* to which it is fixed by means of a pin 12. The spindle *s* is fixed to the armature and is preferably rotary to the extent of about one-quarter rotation. The spindle is retracted by the 65 coiled spring 20, one end of which is fixed to the spindle, the other end being fixed to a pin 21 fast in block *b*. In the type shown, when the armature *a* with semaphore *t* is in a closed circuit position the pole pieces *p*, *p*, 70 exert a turning effort on armature *a* and the semaphore *t* is in the position shown in Fig. 1. When the magnet is de-energized the semaphore is turned by the tension of the spring at right angles to the position shown. The 75 brass block *b* besides forming a bearing for the spindle *s* forms the frame for two spring jack sockets *j* and *k*, see Fig. 2, which are bored as shown from opposite ends and upon 80 opposite sides of the spindle *s*.

30 and 31 are two metal springs fixed to the frame *f* by screws 32, 33, respectively. Spring 30 engages a contact point 34 on the block *b*; 35 is a contact point on the opposite side of block *b* with which spring 31 engages. 85 The main circuit enters via 36 and passes to spring 30, to point 34, through block *b* and pin 35 to spring 31 thence via 43, coils of magnet *m*, 37, to screw posts 38, and return wire 39. When a double contact jack plug *q* 90 is inserted, see Fig. 6, one contact of the plug engages with the frame formed of the block *b* and the other contact of the plug *q* lifts the spring 30 or 31 from its contact and thereby includes the apparatus with which the plug *q* 95 is connected in the circuit. When the parts are in the position shown in Fig. 1, the normal position, the projection *n* connected with the semaphore *t* through block *i* lies parallel and between the plug sockets *k* and *j*. When 100 the parts are in the indicating position as shown in Fig. 3, the circuit having been broken or changed as regards its normal electrical condition, the projection *n* lies across the plug sockets *k* and *j* and a plug inserted in 105 either *k* or *j* engages the projection at one side of its supporting spindle *s* and rotates the spindle thus resetting the annunciator by

the act of inserting the plug, and this resetting operation may take place from either side of the instrument.

In Figs. 7 and 8 there is shown the well known arrangement of quartet table commonly employed in the operating rooms of the large telegraph systems. On each division of the table there is a set of telegraph instruments composed of a relay 40, key 41 and sounder 42 operated by the relay through a local circuit of well known arrangement. The key and relay is connected to a flexible cord *c* which terminates in a jack plug *q*. On top of the wall or partition dividing the table is a row of annunciators *e*, like that described, vertically arranged. Each is included in a separate telegraph circuit *d*, these circuits are led to the annunciators through cables *h* in a well known manner. When the normal electric condition of any one of these circuits *d* is changed in a predetermined manner, as by varying the current, or the normal condition of the circuit, the annunciator responds and the operator on either one side or the other of the table plugs into the jack, and thus resets the annunciator, answers the "call" and then withdraws the plug.

In addition to the visual indication of the semaphore *t* there is also employed an alarm circuit 50, Fig. 1, containing an electro-magnetic bell of any known arrangement and construction connected with the circuit 50 in series with a source of electricity. There is a circuit closer carried by the circular block *i*, this consists of a helical expansion spring 53 in a cylindrical perforation extending through the circular block *i* on the line of a diameter. 54 and 55 are two polished metal balls of too great diameter to be forced out of the cylindrical bore at its contracted terminals. When the block *i* is in the position shown circuit passes through the contacts 51 and 52 and through the balls 54 and 55 and the spring 53 whereby the circuit is completed; when the semaphore is restored to normal position the circuit is broken at a point between the balls and the contacts 51 and 52, respectively.

What I claim and desire to secure by Letters Patent is:

1. In an annunciator the combination of a suitable semaphore, a rotatable support therefor, an electro-magnet controlling said support, a pair of spring jacks opening from opposite sides and means whereby the insertion of a jack plug sets the semaphore.

2. In an annunciator the combination of a

suitable semaphore, a rotatable support therefor, an electro-magnet controlling said support, a pair of spring jacks opening upon different sides, and means whereby the insertion of a jack-plug in either opening restores the semaphore.

3. The combination in an annunciator of an indicating device, an electro-magnet, a pair of spring-jacks opening in different directions and means whereby the insertion of a jack plug in either spring jack resets the indicator.

4. The combination with a suitable switching apparatus of an annunciator consisting of an indicating device, a controlling magnet and a circuit closer for an alarm circuit, said circuit closer consisting of a pair of fixed contacts, a pair of balls, a coiled expansion spring between said balls and a device fixed to said indicator for holding the balls and spring in fixed position with respect to each other.

5. In an annunciator the combination of a suitable semaphore, a vertical rotating support therefor, a controlling magnet, a retracting spring for the support, a spring jack in close proximity to the support and a projection on the support moving in the path of the spring jack plug.

6. In an annunciator the combination of a suitable semaphore, a vertical rotating support therefor, a controlling magnet, a retracting spring for said support, a spring jack in close proximity to the support and a projection on the support in the path of the spring jack plug.

7. In an annunciator the combination of a suitable semaphore, a rotating support therefor, a controlling magnet, a retracting spring for the support, a pair of spring jacks in close proximity to the support on different sides thereof opening in opposite directions, a projection on the support extending in opposite directions, the opposite sides or edges being in the path of the two spring jack plugs, respectively.

8. In an annunciator the combination of a semaphore or drop, an electric circuit, an electro-magnet and means to cut into the circuit from two or more sides of the annunciator and simultaneously reset the semaphore or drop.

JOHN T. NEEDHAM.
